UNITED STATES PATENT OFFICE.

JOHN R. SOURBY AND ROBERT J. RILEY, OF ZION CITY, ILLINOIS.

FLY-TRAP.

No. 821,965.

Specification of Letters Patent.

Patented May 29, 1906.

Application filed May 22 1905. Serial No. 261,562.

To all whom it may concern:

Be it known that we, JOHN R. SOURBY, a subject of the King of Great Britain, and ROBERT J. RILEY, a citizen of the United States, both residing at Zion City, in the county of Lake and State of Illinois, have invented a new and useful Fly-Trap, of which the following is a specification.

The invention relates to improvements in fly-traps.

The object of the present invention is to improve the construction of fly-traps and to provide a simple, inexpensive, and efficient fly-trap of great strength and durability designed to take the place of poison, adhesive fly-paper, and like annoying or dangerous means and adapted to be hung on a screen-door or the exterior of a window for catching flies before the same have entered a house.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

In the drawings, Figure 1 is a perspective view of a fly-trap constructed in accordance with this invention. Fig. 2 is a rear elevation of the same. Fig. 3 is a vertical sectional view. Fig. 4 is a horizontal sectional view on the line 4-4 of Fig. 3. Fig. 5 is an elevation of another form of the invention, showing the fly-trap applied to a screen-door and extending entirely across the top of the same. Fig. 6 is a vertical longitudinal sectional view of the fly-trap shown in Fig. 5. Fig. 7 is an enlarged perspective view of one end of the same, the front wall being broken away to illustrate the construction of the fly-trapping devices more clearly. Fig. 8 is an enlarged vertical sectional view taken substantially on the line 8-8 of Fig. 6, the sides or clamping-flanges of the longitudinally-folded top and bottom bars of the marginal frame being open to illustrate the construction more clearly.

Like numerals of reference designate corresponding parts in all the figures of the drawings.

1 designates a fly-trap of substantially tri-

angular or pyramidal form composed of front and rear walls 2 and 3, of wire-gauze, united at their side edges and supported by the side bars 4 of a triangular frame. The triangular frame is composed of the side bars 4 and a connecting bottom bar 5, and it is constructed of sheet metal, the bars being folded longitudinally to provide two clamping-flanges, between which the edges of the wire-gauze are secured. The wire-gauze is retained between the flanges of the side and bottom bars by indenting the latter, as indicated; but suitable fastening means may be provided, if desired, for positively securing the wire-gauze to the bars of the triangular frame.

The front wall 3 of the trap is bowed outwardly, and the rear wall is flat to enable the device to fit flat against a screen-door, window-pane, or the like, and the front and rear walls are spaced apart at the bottom of the trap to provide a large opening or entrance 6 for the flies. By this construction the flies or other insects crawling upward will be caused to enter the bottom of the trap.

Within the lower portion of the trap is arranged an upwardly-extending tapered fly-trapping device 7, which is approximately triangular or pyramidal and which consists of integral inturned portions or extensions of the front and rear walls of the trap. The tapering inturned portions or extensions of the front and rear walls of the trap are united at their upwardly-converging side edges by means of a roll or bead 8; but any other suitable means may be employed for this purpose. An opening 9 is provided at the top or apex of the upwardly-extending trapping device, and the flies enter the body of the trap through the said opening 9 and will be effectively prevented from returning.

The rear wall of the trap is cut away at the top to provide a triangular opening 10, which is normally covered by a pivoted door 11 of triangular form, the top being adapted to be swung on its pivot 12, as indicated in dotted lines in Fig. 2 of the drawings, when it is desired to empty the trap. The upper edge 13 of the rear wall is supported by a transverse strip or bar 14 and is secured to the same by means of a clip 15 or other suitable fastening device. The pivot 12 consists of a rivet or other suitable fastening device, which also secures a hanger 16 to the top of the trap. The hanger is provided with a suitable opening and is adapted to enable the trap to be readily secured to a screen-door or to a window.

It is also adapted to be hung up in a room and may be used at any desired place.

In Figs. 5 to 8, inclusive, is illustrated the preferred form of the invention, the fly-trap 17 being extended entirely across a screen-door 18. The fly-trap is constructed substantially the same as that heretofore described, except that it is extended entirely across the screen to which it is applied and is provided with a plurality of fly-trapping devices 19. It is composed of front and rear walls 20 and 21, united at their side edges and supported by a marginal frame 22. The marginal frame is composed of top, bottom, and side bars constructed of sheet metal and folded longitudinally to provide two clamping-flanges, between which the edges of the wire-gauze are secured, as before described. The front wall 20 is bowed outwardly, and the rear wall is flat and is adapted to fit close against the screen. The screen-door is provided with a transverse cleat 23, located at the bottom of the trap and adapted to prevent flies from crawling upward into the space between the back of the trap and the screen material of the screen-door. The front and rear walls are spaced apart at the bottom of the trap to provide a large opening or entrance for the flies, so that flies or other insects crawling upward on the screen-door will be caused to enter the trap.

The fly-trapping devices 19, which are arranged in a row or series, are approximately triangular or pyramidal and are formed by integral inturned portions or extensions of the front and rear walls of the trap. The extensions of the front and rear walls are cut to form tapered inturned portions, which are united at their upwardly-converging side edges by means of a roll or bead 24 or other suitable means, as before described. The tops of the fly-trapping devices 19 are provided with openings 25, through which the upwardly-crawling insects pass, and when they enter the trap they are effectually prevented from returning.

The rear wall of the trap is provided with a circular opening 26, which is normally covered by a circular door 27, secured to the back of the trap by a pivot 28, which also serves as the attaching means for a hanger 29. The door and the hanger are located near one end of the trap to facilitate removing the contents thereof. The trap is also provided at the other end with a hanger 30. The hangers 29 and 30 are perforated for the reception of screws or other suitable fastening devices for detachably securing the trap to a screen-door or window-screen, and they are preferably fastened to the top bar of the screen-frame, as clearly shown in Fig. 5 of the drawings. The end bars 31 of the marginal frame of the trap are curved, as shown, to facilitate the attachment of the bowed end portions of the front wall to the end edges of the rear

wall. The trap 17 is adapted to be applied to both screen-doors and window-screens, and while it is shown in the accompanying drawings at the top it may be placed at any other desired point, or a plurality of traps 70 may be provided.

It will be seen that the fly-trap is exceedingly simple and inexpensive in construction and that it possesses great strength and durability and will not get out of order. Also 75 it will be clear that flies and other insects will be caused to crawl into the interior of the trap and that the latter may be readily emptied when desired.

Having thus fully described our invention, 80 what we claim as new, and desire to secure by Letters Patent, is—

1. A fly-trap composed of front and rear walls connected together at their side edges and spaced apart at the bottom to provide a 85 large opening or entrance, and a trapping device extending into the trap at the opening or entrance and having a small opening.

2. A fly-trap composed of front and rear walls connected together at their side edges and spaced apart at the bottom to provide a 90 large opening or entrance, and a trapping device located at the said opening or entrance and consisting of inturned extensions of the front and rear walls.

3. A fly-trap having an upwardly-tapered body and composed of a flat rear wall and an outwardly-bowed front wall secured at the side edges to the side edges of the rear wall, said front and rear walls being spaced apart 100 at their lower edges to provide a large entrance or opening, and a tapering trapping device extending into the trap from the bottom thereof at the entrance or opening and provided with a small opening.

4. A fly-trap having a tapered body and comprising front and rear walls united at their side edges and spaced apart at the bottom, a marginal supporting frame receiving and securing the contiguous side edges of the said walls together, and a trapping device extending into the trap from the bottom entrance or opening.

5. A trap, comprising a body provided at the upper portion with an opening, a hanger 115 located at the opening, a door for covering the opening, and a fastening device securing the hanger to the trap and forming a pivot for the door.

6. A trap having a body and comprising 120 an outwardly-bowed front wall and a flat rear wall, said walls being secured together at their side edges and spaced apart at the bottom and provided thereat with inturned tapering extensions also united at the side 125 edges to form a trapping device, the latter being provided at the top with an opening.

7. A fly-trap composed of front and rear walls secured together at their side edges and spaced apart at the bottom to provide a large 130

opening or entrance, and a plurality of trapping devices extending into the trap at the opening or entrance thereof and provided with small openings communicating with the interior of the trap.

5 8. A fly-trap composed of front and rear walls spaced apart at the bottom to form a large opening or entrance, said front and rear walls being provided at the opening or entrance with inturned extensions cut away or recessed to form corresponding tapered portions, the latter being secured together at their side edges and forming a plurality of trapping devices.

15 9. The combination with a screen, of a removable trap extending entirely across the same and provided at the bottom with an en-

larged entrance or opening, said trap being also provided at the enlarged entrance or opening with a plurality of inwardly-extending tapering fly-trapping devices connected with and supported by the walls of the trap, each fly-trapping device consisting of two tapering pieces secured together at their side edges.

20 25 In testimony that we claim the foregoing as our own we have hereto affixed our signatures in the presence of two witnesses.

JOHN R. SOURBY.
ROBERT J. RILEY.
